UNITED STATES PATENT OFFICE.

RALEIGH J. HIMMELRIGHT, OF NEW YORK, N. Y., ASSIGNOR TO AMERICAN ARCH COMPANY, OF NEW YORK, N. Y., A CORPORATION OF DELAWARE.

LOCOMOTIVE-FIREBOX.

1,369,105.

Specification of Letters Patent. Patented Feb. 22, 1921.

Application filed May 4, 1917. Serial No. 166,307.

To all whom it may concern:

Be it known that I, RALEIGH J. HIMMELRIGHT, a citizen of the United States, residing at New York city, in the county of 5 New York and State of New York, have invented certain new and useful Improvements in Locomotive-Fireboxes, of which the following is a specification.

This invention relates to improvements in 10 locomotive fire boxes and has particular reference to fire boxes of the Gaines type, in which the fire box is divided into a fire chamber and a combustion chamber by means of a bridge wall extending across the 15 fire box intermediate the flue sheet and the end of the grates, means being provided in said bridge wall for introducing an additional supply of air.

This invention embodies the same generic 20 idea of automatically controlling the introduction of the additional supply of air, as is disclosed in my co-pending application, Serial Number 166,305, filed May 4th, 1917, but the specific mechanism employed to obtain 25 such automatic control is different from that shown in said application.

One of the primary objects, therefore, of the present invention, resides in the provision of novel and effective means for automatically controlling the supply of additional air in such manner that economy in fuel consumption and better combustion, with the consequent increase in general efficiency, are obtained.

Another of the objects of the invention 35 resides in providing means whereby the secondary air supply is introduced when the engine is using steam only.

My invention also contemplates the pre- 40 heating or super-heating of the air which is introduced through the bridge wall.

I accomplish the foregoing, together with such other objects as may hereinafter appear, by means of a construction illustrated 45 in preferred form in the accompanying drawings, wherein:—

Figure 1 is a longitudinal section through a locomotive fire box of the Gaines type with my improvements applied thereto; Fig. 50 2 is a horizontal section through the fire box; Figs. 3 and 4 are sectional views of details of the invention; and Fig. 5 is a modification of my invention.

Referring now to Fig. 1, it will be seen 55 that the fire box comprises the usual flue

sheet 7, side sheets 8, back sheet 9, and crown sheet 10. The refractory bridge wall 11 which divides the fire box into the fire chamber A and the combustion chamber B, is carried on the cross bearer 12 supported 60 from the inside of the mud ring 13, such bridge wall extending across the fire box, and being located in advance of the grates 14. The bridge wall is composed of fire 65 brick or other suitable refractory material and is carried up to the circulation tubes 15 where it coöperates with the rearwardly extending brick arch 16 supported on the tubes. In the bottom of the combustion chamber B is a discharge hopper 17 for the 70 removal of deposit. Additional quantities of air are introduced in the fire chamber A through the bridge wall 11 by one or more air pipes 18. Coupled to the pipe or pipes 18 is a main supply pipe 19, the front end 75 of which extends to a point in advance of the front water leg 20, the intermediate portions of such pipe being arranged in the form of a coil 19^a lying in the bottom of the combustion chamber B, in such manner as 80 not to interfere with the discharge hopper 17, as will be clear from inspection of Fig. 2. The bottom of each of the supply pipes 18 is closed by a weighted valve 21, normally held in closed position, but which will automatically open to discharge any deposit or 85 broken brick or other material which may collect in the pipes 18.

The passage of air through the pipe 19 is controlled by means of the valve mechanism 90 22, which in its simplest form consists of a disk 23, provided with the operating link 24 and an operating piston rod 25, such piston rod being provided with a rack portion 26 adapted to be engaged by the segment 27. 95 The segment 27 is provided with a weighted arm 28 which normally by gravity holds the valve in closed position, cutting off the supply through pipe 19. The rod 25 is operated by the piston 29 in cylinder 30, steam being 100 introduced from the steam pipe (not shown) by means of the pipe 31. The segment 27 is carried by the arm 32 supported from the cylinder 30.

The operation is as follows: When the 105 locomotive is standing sufficient air is supplied through the grates 14 for the economical maintenance of the fire, but when the engine is working, additional quantities of air must be introduced in order to obtain eco- 110

nomical operation and efficiency. By my present invention, the additional quantities of air are introduced through the pipe 19 when the engine is using steam, in which 5 event, steam from the steam pipe entering the cylinder 30 via pipe 31 forces the piston 29 to the left, thus causing the valve disk 23 to be opened through its operating mechanism, as will be readily understood. The 10 suction in the fire chamber will draw additional quantities of air through pipe 19, coil 19^a, and pipe 18, when the valve is thus opened. It will be apparent that the degree to which the valve disk 23 is opened 15 will be dependent upon the particular working conditions of the engine, because the pressure acting upon piston 29 will vary within considerable limits depending upon the degree of throttle opening being used, 20 the speed of the locomotive, etc., and by properly arranging the weighted arm 28 with respect to such pressure, the degree of opening of the valve 23 can be automatically controlled. As a result of this, additional 25 air will be supplied in proportion to the demands, as evidenced by the pressure of the working steam admitted to the piston 29. Thus, if the engine is working hard, the valve disk 23 will be more widely open than 30 when the engine is working easily.

In this connection, it will, of course, be understood that the weighted arm 28 will move the valve disk 23 to closed position when the engine is not using steam, and will 35 also compensate for any variations in steam pressure in the cylinder 30. Thus, for example, if the steam pressure in the pipe 31 should drop when the engine is not working so hard, the weighted arm 28 will correspondingly return the valve disk 23 toward 40 its seat. From the foregoing, it will be noted that the control mechanism is such that the volume of additional air will always be in proportion to the demands of the particular working conditions of the engine, 45 which tends to maintain maximum efficiency at all times.

The preheating of the additional air supply, as it passes through the heating coil 19^a, 50 also tends toward the production of better combustion and general efficiency and is far more advantageous than introducing cold air, as will be readily understood by those familiar with this art.

If desired, the additional air supplied 55 through pipe 19 under the control of valve mechanism operated from working steam, may be forced into the fire chamber by steam as indicated in Fig. 5. In this modification,

the valve mechanism and means for operating it, are the same as shown in Fig. 1, but a steam pipe 33, leading from the steam chest or other source of working pressure, is provided for introducing a jet of steam into the pipe 19 on the fire box side of the valve 65 mechanism, the end of the pipe being bent in the manner indicated in Fig. 5. The pipe 33 is controlled by a valve 34 which is operated from the arm 24 by means of the link 35. When, therefore, the valve 23 is opened 70 when the engine is using steam, the valve 34 will also be opened, and steam will be delivered into the pipe 19 in such manner as to entrain additional supply of air and force the same into the fire chamber, somewhat 75 after the manner of an injector.

I claim:

1. The combination with a locomotive fire box having a transverse bridge wall or baffle to the rear of the flue sheet dividing the fire box into a combustion chamber and a fire chamber, of an air inlet passage extending upwardly from the atmosphere through the bridge wall, and a conduit for supplying said inlet passage with supplemental air, a 80 portion of said conduit being extended upwardly from its connection to the inlet passage and lying within the combustion chamber.

2. The combination with a locomotive fire box having a supplemental air inlet passage, of a valve for controlling said passage, means for introducing a jet of steam into the passage, a valve for controlling said jet, a piston for opening both of said valves, and 95 means for subjecting the piston to the pressure of the working steam when the locomotive is operating.

3. The combination with a locomotive fire box having means for introducing an additional supply of air therein, of means for regulating said air supply including a valve, means for opening said valve, and means for subjecting said opening means to live steam pressure when the locomotive is being operated.

4. The combination with a locomotive fire box having a supplemental air inlet passage, of a valve for controlling said passage, means for introducing a jet of steam into 110 the passage, a valve for controlling said jet, means for opening both of said valves, and means for subjecting said opening means to the pressure of the working steam when the locomotive is operating.

In testimony whereof I have hereunto signed my name.

RALEIGH J. HIMMELRIGHT.
